DESIGN FOR A PLATFORM SCALE

Arthur C. Haggstrom, Rockford, Ill., assignor to
Clarence E. Threedy, Rockford, Ill., as trustee

Application October 4, 1945, Serial No. 122,516

Term of patent 14 years

(CL. D52—10)

To all whom it may concern:

Be it known that I, Arthur C. Haggstrom, a citizen of the United States and a resident of Rockford, in the county of Winnebago and State of Illinois, have invented a new, original, and ornamental Design for a Platform Scale, of which the following is a specification, reference being had to the accompanying drawing, forming a part thereof, and in which:

Fig. 1 is a front perspective view of a platform scale, showing my new design;

Fig. 2 is a rear perspective view of the same.

I claim:

The ornamental design for a platform scale, as shown.

ARTHUR C. HAGGSTROM.
